(57) **CLAIM**

I claim the ornamental design for a thermally-insulated beverage container, as shown and described.

DESCRIPTION

FIG. 1 is a front view of the thermally-insulated beverage container.

FIG. 2 is a back view of the claimed design.

FIG. 3 is a left side view of the claimed design.

FIG. 4 is top view of the claimed design.

FIG. 5 is a bottom view of the claimed design; and,

FIG. 6 is a perspective view of the claimed design.

1 Claim, 5 Drawing Sheets

FIG. 1

FIG. 2

FIG. 3

FIG. 4

FIG. 5

FIG. 6
